ABSTRACT OF THE DISCLOSURE

A process for controlling the feeding of alumina to a reduction cell comprising determining a smoothed cell resistance, comparing the cell resistance with the lowest base level resistance and, when the difference exceeds a predetermined amount ΔR^* , feeding alumina to the cell. The value of ΔR^* is varied according to the noise level of the cell.

BACKGROUND OF THE INVENTION

This invention relates to the control of an aluminum reduction cell. The production of aluminum by the electrolysis of alumina dissolved in a molten salt electrolyte such as cryolite is an old and well-known process commonly termed the "Hall-Heroult process." The alumina, which is dissolved in an electrolyte, breaks down into its components, the oxygen being liberated at the anode and the metallic aluminum being deposited in a pool of molten metal which forms in the cavity of the electrolytic cell. The liberated oxygen combines with the carbon of the anodes to form a mixture of carbon dioxide and carbon monoxide which evolves from the cell. The pool of molten metal at the cavity of the cell in effect constitutes the cathode of the cell.

The conventional aluminum reduction cell comprises a steel shell, a current-carrying carbonaceous lining disposed therein, and one or more movable anodes disposed within the cavity defined by the carbonaceous lining. The carbonaceous cathode lining may be a monolithic lining, which is tamped into place and baked in during the operation of the cell, or it may be composed of carbonaceous blocks which have been baked prior to installation of the cell. A plurality of conductor bars are embedded in the cathode lining. Frequently, insulating material such as granular alumina is disposed between the steel shell and the carbonaceous lining to conserve the heat generated during the electrolytic process.

Between about 80 and 90% of the electrolyte composition normally consists of a cryolite which is a mixture of sodium and aluminum fluoride (Na_3AlF_6). Excess sodium fluoride results in a loss of efficiency and, therefore, it is the usual practice to add an excess of aluminum fluoride to prevent this loss of efficiency. Due to its volatility, however, aluminum fluoride is usually added in restricted amounts, for example, up to 10% in excess of the stoichiometric amount of aluminum fluoride in cryolite. Small amounts of calcium fluoride are added to lower the liquidus temperature of the electrolyte. A lithium compound such as lithium fluoride, lithium carbonate and the like is frequently added to the electrolyte to improve the conductivity thereof. A crust of solidified electrolyte and alumina forms on the surface of the bath and the crust is usually covered over with additional alumina to preheat the alumina prior to its introduction into the electrolyte and to conserve heat.

As the electrolysis proceeds, alumina is consumed in direct proportion to the metal production. As the alumina concentration in the electrolyte is reduced, a point is reached where a phenomenon known as an "anode effect" occurs. The voltage drop across the cell, which normally

2

runs between 4 and 5 volts, rises rapidly to a level of about 40 volts or more. This effect is generally attributed to a low concentration of alumina in the electrolyte. The actual concentration of alumina in the electrolyte at which this effect occurs seems to depend upon the temperature and composition of the electrolyte, the current density, and the like, but it usually occurs at an alumina concentration below about 2% by weight of the electrolyte. The anode effect is generally terminated by the addition of more alumina. This may be done manually or automatically. The frozen crust, which covers the electrolyte, is broken by a suitable crust breaker and the alumina, which has been previously distributed to the top of the crust, falls into the electrolyte. Frequently, the addition of alumina is accompanied by vigorous stirring of the electrolyte to remove the gas film which forms on anode surfaces. This technique quickly causes the anode effect to disappear. The disadvantages of the anode effect are many and varied. One of the major disadvantages is the large power consumption during the period of the anode effect which is unproductive. Other disadvantages include overheating of the electrolyte and the loss of bath components by volatilization. Moreover, because in the usual aluminum reduction plant a large group of reduction cells are connected electrically in a series, any major upset of one cell affects the other cells in the series.

Although the anode effect presents serious problems in the control of aluminum reduction cells, this phenomenon is generally a less serious commercial problem than the severe overfeeding of alumina to the cell. A severely overfed cell is commonly termed "sick pot" or "sick cell." If a cell is severely overfed, the alumina does not dissolve in the electrolyte and tends to settle at the bottom of the cell seriously disrupting the current distribution, reducing current efficiency, reducing metal production, increasing anode carbon burnoff and generally reducing cathode life. While it may take a short period, e.g. 5 to 10 minutes, to manually terminate an anode effect, a sick cell takes considerable time to return to normal operations. Thus it is the usual industrial practice to operate at the lower part of the alumina concentration range to specifically avoid the pot condition. Indeed, many automatic control strategies attempt to promote at least one anode effect per day, specifically to prevent the overfeeding of alumina to the cell.

One of the most efficient control techniques which has been developed for aluminum reduction cells is that described in the copending application of D. R. Bristol et al., Ser. No. 731,901, now U.S. Pat. No. 3,625,842. In the procedure described, the resistance of the cell is periodically calculated from voltage and current values. When the resistance has increased a particular predetermined amount then alumina would be added to the cell. In the preferred embodiment of this process periodic resistance values R_i are calculated from the equation

$$R_i = \frac{V_i - A}{I_i} \quad (1)$$

where

65 R_i is the resistance in ohms,
 V_i is the measured cell voltage,
 I_i is the measured cell current, and
 A is the back electromotive force.

From a series of R_i values a base level resistance R_B is 70 periodically determined by suitable smoothing or averaging techniques. Periodically, an averaged or smoothed cell resistance R_i is derived from several sequential R_i

values. The smoothed cell resistance R_I is periodically compared with the lowest previously determined R_B values for the particular cycle, and when this difference, herein termed ΔR , exceeds a predetermined value, herein termed ΔR^* , alumina is added to the cell. Although analog-type computing devices can be employed to calculate and average or smooth the various resistance values, digital computing devices have been used almost universally. Although the back electromotive force, A , varies somewhat according to the alumina concentration in the electrolyte, it is presumed to be constant for purposes of the above calculation. A typical value of A is 1.6 volts.

The control techniques described by Bristol et al. were a significant advance in the art of controlling an aluminum reduction cell, but serious problems were found in the commercial embodiment of this technique. It was found that despite filtering the voltage and current measurements, as well as the various smoothing or averaging techniques used in calculating the various resistance values used in the control program, the control program became confused during periods when the noise level of the cell was higher than normal. The control strategy tended to overfeed the cell during periods of unstable operation which are characterized by a high noise level. An overfed cell tends to become increasingly noisy, and therefore the problem of overfeeding is quickly magnified. Unless the cell operators take timely corrective action, the continuous overfeeding of an unstable cell will rapidly create a sick cell. Therefore, in the commercial application of this control technique, it was found necessary to remove the cell from automatic feed control when the noise level of the cell became extremely high. In one commercial potline in which 144 cells are connected in a series, it was found that from up to 40% of the cells were off automatic control at any one particular time due to the high noise level of the cell.

As used herein, the expression "noise," and terms of similar import, refers to the deviation or fluctuation of the electrical characteristics of the cell over a period of time. These fluctuations are commonly termed the A.C. component. These characteristics of the cell can be current, voltage or resistance. A high noise level can result from many factors other than overfeeding such as improperly set anodes, small anode to cathode distance, low metal pad, low bath, and the like. To give up indication of the magnitude of noise in a reduction cell, the fluctuation in resistance (noise) is generally larger than the value of ΔR^* . For example, in a stable cell the noise can be 0.5 micro-ohms and the ΔR^* can be 0.3 micro-ohms. The noise of an unstable cell in resistance units can exceed 4 micro-ohms.

Against this background the present invention was developed.

DESCRIPTION OF THE INVENTION

This invention is directed to an improvement in the automatic control of an aluminum reduction cell wherein the cell resistance is calculated from the cell current and cell voltage, the cell resistance is compared with a base level resistance, and if the difference is greater than ΔR^* , cell parameters such as alumina concentration are changed. More particularly, this invention relates to a method of determining the set point for the difference in resistance to provide improved cell control. The present invention minimizes the tendency of overfeeding of alumina to the cell when the noise level of the cell becomes higher than normal.

The inventors have found that by varying the setpoint ΔR^* , the criterion for feeding alumina to the cell, in accordance with the noise level of the cell, that the tendency to overfeed is significantly reduced. It has been found that, as the noise level increases, the ΔR^* set point must be increased accordingly.

In accordance with this invention the set point for

changing a cell parameter, and in particular alumina concentration, ΔR^* , or the demand feed criterion, is determined from the general equation:

$$\Delta R^* = a + b(N_I)^m \quad (2)$$

where

a and b are predetermined constants, and N_I (Noise Index) is a measure of the fluctuations or the A.C. component of an electrical characteristic of the cell over a period of time, and m is a number from 1 to 2.5.

The constants a and b and the exponent m will be chosen according to the characteristics of the cell such as cell size, cell design, and the like. If it is desired to have a greater sensitivity to noise, it may be desirable to use a larger number for the exponent m . In controlling an experimental 170,000 ampere cell in accordance with this invention, the constant a was set at 0.25, the constant b was set at 0.36, and the exponent was set at 1. The Noise Index varied from 0.5 micro-ohms for a stable condition to 50 micro-ohms for a highly unstable condition.

In the preferred embodiment of the invention, the reduction cell is scanned periodically (e.g. every 2 to 12 seconds) to measure the cell voltage and the cell current, and, using these values in equation (1), calculating resistance R_I . A base level resistance R_B is obtained by a smoothing technique from a series of R_I values which have been calculated over a period of time, (e.g. 2 minutes). A smoothed cell resistance R_I is obtained also by a smoothing technique from a series of R_I values which have been calculated over a second interval of time, normally shorter than the first interval (e.g. 16 seconds or 8 scans). R_I is compared with a lowest previously determined R_B , and if the difference ΔR is greater than the demand feed criterion ΔR^* , then alumina is fed to the cell. An alternate, but equivalent, procedure involves deriving the R_B and R_I from equation (1) utilizing smoothed voltage and current values. However, this procedure is less desirable because it increases data storage requirements and, because both voltage and current values must be smoothed, involves twice as many smoothing operations as the preferred method described above.

As used herein, the term "smoothing" or words of similar import, refer to the electrical, mechanical, electro-mechanical and mathematical techniques for determining a representative value from a number of such values or predicting the next value from a series of such values. Included in this terminology are mathematical methods such as averaging and predicting techniques which are described in *Data Smoothing and Prediction* by R. B. Blackman (1965). A predicting technique is preferred in determining R_I . A predicted value will generally be slightly higher than an averaged value because the resistance is gradually rising during most of the control-cycle. Thus the ΔR^* when averaged values are utilized will be smaller than when a predicted value is utilized.

Periodically, the criterion for feeding alumina, ΔR^* , is updated and changed in accordance with equation (2) or its equivalent. The noise index N_I in equation (2) is a measure of the deviation or A.C. component of the electrical characteristics. It may be the absolute maximum deviation of R_I values over a period of time, it may be the maximum deviation of R_I values over a period of time from an averaged or smoothed value such as R_I , it may be a summation or average of the absolute value of these deviations over a period of time, or it may be a filtered deviation of R_I values from R_I values. Similar measures of the variation of voltage or current could be used. However, the constant b would have to be adjusted to compensate for the different units.

With reference to FIG. 1, which shows a schematic diagram of a computer controlled reduction cell, it may be seen that the cell 10 comprises a metal shell 11, an insulating layer 12 which can be of any desired refractory

material, usually alumina, disposed within said shell and a conductive lining 13 disposed therein, preferably carbonaceous in nature. Within the cavity defined by conductive lining 13 are a pool of molten metal 14 at the bottom of said cavity, a body of molten electrolyte 15 disposed thereon, and a crust 16 composed of frozen electrolyte and alumina disposed on top of the molten electrolyte. Partially immersed in the electrolyte are carbonaceous anodes 17 which are electrically connected to the bus bar 19 by anode rods 18 and supported thereby. (Means to connect the anode rod to the bus bar are not shown.) Disposed within the carbonaceous cell lining 13 are cathodic current collecting bars 20, the outer ends of which project out of the shell 11. The exposed ends of the conductor bars 20 are electrically connected to the anode bus bar of the next cell by suitable means not shown. The anode bus bar 19 is electrically connected to the cathodic conductor bars of the prior cell in the pot line by means not shown.

As shown in FIG. 1, the cell is provided with a current sensing device 21 which is suitably connected to the anode bus bar 19. A voltage sensing device 22 is connected between the anode bus bar 19 and the cathodic conductor bars 20. The current sensing device and voltage sensing device are operably connected to a computer device 23. The computing device may be an analog or digital device, although the digital computing means is preferred because of its speed and data storage capacity. The current and voltage sensing means 21 and 22 may be of any suitable means for performing these functions. However, if the computing device 23 is digital in nature and the output of the sensing devices is analog, suitable analog to digital converters are employed to render the devices compatible. A multiplexing unit (not shown) may be employed to monitor the voltage and current sensing means of each cell of the pot line. The computing device 23 may be provided with suitable input and readout devices.

The computing device may be, and usually is, programmed to provide many functions in addition to those described herein. For example, the computer program may have subroutines to control the anode to cathode distance, optimize the back of electromotive force value, optimize current distribution in the anodes, and the like. However, in the present invention, the computing device has two prime functions and these are to generate a signal for feeding alumina when the cell resistance rises to the point when an anode effect is approaching, and to adjust the criterion for feeding alumina in accordance with the noise level of the cell.

FIG. 2 is a simplified flow diagram of the various steps involved in the operations of a typical computer program for the present invention for a single reduction cell. This type of flow diagram is commonly prepared by programmers prior to writing the detailed computer program. In this figure the rectangles are used to designate a calculating, or operating, step and the diamond shape indicates a comparing step. The program begins at point A. In block 100 the counter K is set at a value of 1 and the lowest base level resistance R_{BL} is set at an arbitrary value of 100, a value considerably higher than normal resistance observations. In the operation of block 101 the cell is scanned and the voltage V_I and the current I_I are measured. These values are used in block 102 to determine the cell resistance R_I . K is then compared with a predetermined value n in diamond 103, and if K is less than n , K is increased by 1 as shown in block 104. The cell is again scanned, to measure current and voltage and the cell resistance is again calculated. This loop continues until the number of scans n is reached. When K is equal to or greater than n , the program proceeds to block 105 wherein the smoothed cell resistance R_I is calculated by a suitable smoothing technique from the last nR_I values. The deviation of the resistance during the scanning period, ΔR_I , is calculated in block 106 by subtracting the most recently determined cell resistance R_I from the smoothed resistance R_I . Supplement to calculating ΔR_I , the counter K is com-

pared in diamond 107 with nn , and if K is not equal or greater than nn , as indicated in block 108, K is increased by one and the program reverts to point B. If K is equal to or greater than nn , the program proceeds to block 109 wherein the base level resistance R_B is calculated from the last nn values of smoothed resistances R_I . The noise index N_I is calculated in block 110 by averaging the absolute values of the ΔR_I previously calculated during the scan period. In the comparison step of 111, if the base level resistance R_B is less than the lowest base level resistance R_{BL} , then the old value of R_{BL} is replaced by the calculated base level resistance and the program reverts to point B. If the base level resistance R_B is greater than the lowest base level resistance R_{BL} , then the program proceeds to block 113 wherein the demand feed criterion ΔR^* is calculated. In block 114 the increase in resistance ΔR is calculated by subtracting the lowest base level resistance R_{BL} from the smoothed resistance R_I . As shown in diamond 115, if ΔR is greater than the demand feed criterion ΔR^* , then the program proceeds to block 116 where the feed indicator is activated for the feeding of alumina to the cell. The program then reverts to point A and K is reset at 1. If ΔR is not greater than the demand feed criterion, the program reverts to point B. In a typical program, n is normally set at about 8 and the value nn is set at about 128. The cell is scanned normally about every two to twelve seconds to measure voltage and current values.

Usually a delay of up to 10 minutes is programmed to occur after the feed indicator is activated to allow time for the alumina to dissolve in the electrolyte and for the anode-cathode distance to be adjusted.

The process of the present invention lowers the average alumina concentration during upset cell conditions by increasing the average time between feeds and, because of this, the anode effect frequency may increase slightly. However, the small increase in anode effect frequency does not significantly affect the overall efficiency of the control technique.

It is obvious that various modifications and improvements can be made in the above-described invention without departing from the spirit thereof and the scope of the appended claims.

What is claimed is:

1. In the process of controlling the feeding of alumina to an aluminum reduction cell wherein a base level resistance R_B and a smoothed cell resistance R_I are periodically determined from the electrical parameters of the cell, a lowest R_B is determined from a series of R_B values, the difference ΔR between the lowest R_B value and R_I is periodically determined and said difference ΔR is compared with a criterion ΔR^* for feeding alumina to the cell and when ΔR equals or exceeds ΔR^* , alumina is fed to the cell, the improvement comprising
  - (A) sensing the fluctuations of an electrical parameter of the cell selected from the group consisting of cell resistance, cell voltage and cell current over a preselected period of time, and
  - (B) determining ΔR^* from the equation

$$\Delta R^* = a + b(N_I)^m$$

where a and b are predetermined constants, where N_I is a measure of said fluctuations of an electrical parameter, and m is a number from 1 to 2.5.

2. The process of claim 1 wherein the R_B and R_I values are determined from the equation

$$R = \frac{V - A}{I}$$

where

75 R is a resistance in ohms,

V is a smoothed cell voltage,
 I is a smoothed cell current, and
 A is a predetermined back electromotive force.
 3. The process of claim 1 wherein the R_B and R_I values
 are determined from a series of R_I values which are
 determined from the equation

$$R_I = \frac{V_i - A}{I_i}$$

where

R_I is the resistance in ohms,
 V_i is the measured cell voltage,
 I_i is the measured cell current, and

A is a predetermined back electromotive force.
 4. The process of claim 1 wherein N_I is a measure of
 the fluctuation of cell resistance over a preselected period
 of time.
